(57) **CLAIM**

The ornamental design for a pallet cornerboard locator, as shown and described.

DESCRIPTION

FIG. 1 is a front perspective view of a pallet cornerboard locator;

FIG. 2 is a front left perspective view thereof;

FIG. 3 is a top view thereof;

FIG. 4 is a front view thereof;

FIG. 5 is a rear view thereof;

FIG. 6 is a right side view thereof; and,

FIG. 7 is a left side view thereof.

The dash-dash broken lines in the drawings are environmental lines which do not form part of the claimed design. The short dash-long dash lines are boundary lines which do not form part of the claimed design.
